CUPOLA FURNACE

William M. McNeil, Wheaton, Ill., assignor to
United States Gypsum Company, Chicago, Ill.,
a corporation of Illinois

Application September 19, 1941, Serial No. 411,504

14 Claims. (Cl. 263—27)

This invention relates to methods of and apparatus for the production of mineral melt, and has reference more particularly to a combination steam generating furnace and cupola which is useful for the production of mineral wool.

In the production of mineral wool by the blowing of molten mineral matter with steam or other gas, it is customary to charge a mixture of coke and mineral matter into a cupola and to effect the melting of the mineral matter by the combustion of the coke in the cupola. The coke and mineral matter are charged into the cupola in rather large pieces in order to enable combustion gases readily to pass through the fuel bed. It has in the past been impractical to use cheap coal as a fuel since, on heating, the coal has a tendency to become plastic and packs within the cupola so that air and combustion gases will not pass through the fuel bed. Also coal usually contains a high percentage of volatile matter and a large portion of the heat in the coal is not effectively utilized in the cupola because the combustible volatile matter has a tendency to distill off and to pass up the stack. Also, the cupolas of the prior art have generally been charged by hand shoveling thereby materially increasing the labor cost of operating the same.

An object of this invention, therefore, is to provide a combination cupola and furnace which will successfully burn coal as a fuel.

Another object of this invention is to provide a furnace cupola in which fine or coarse mineral matter may be melted to form a molten slag for blowing into mineral wool.

Another object of this invention is to provide a furnace cupola in which the volatile matter is completely burned with the liberation of heat which is utilized to produce steam for blowing molten slag into mineral wool or for other purposes.

Another object of the invention is to provide a furnace cupola in which the coal is preheated to distill off the volatile matter and to produce pieces or chunks of coke and sintered mineral matter which may be discharged into a cupola thereby permitting free passage of air and combustion gases through the fuel bed in the cupola.

A further object of the invention is to provide a furnace cupola in which a mixture of coal and mineral matter is fed automatically into the furnace by means of a stoker, thus greatly reducing the labor cost of producing a mineral melt.

A still further object of this invention is to provide a two stage process of producing mineral wool which is simple and economical.

Further and additional objects will appear from the following description, the accompanying drawings, and the appended claims.

In accordance with one embodiment of this invention, an apparatus has been provided, (1) for subjecting a mixture of carbonaceous material, such as coal, and mineral matter, to a preliminary heating step in order to drive off the combustible volatile matter from the carbonaceous material and to cause a coalescence of the carbonaceous material and mineral matter, (2) for discharging the resulting lumps of consolidated carbonaceous material and mineral matter into a cupola whereby the mineral matter is melted, and (3) for finally discharging the mineral melt from the cupola in a continuous stream. The cupola is provided with steam generating tubes in association with a steam boiler positioned in a combustion chamber above the cupola for providing high pressure steam for disintegrating the molten stream of mineral matter into mineral wool. The volatiles distilled from the mixture of carbonaceous material and mineral matter are burned in the combustion chamber above the cupola and the heat thereby produced, in conjunction with the heat escaping from the cupola, is imparted to the steam boiler in the combustion chamber. Means are also provided for preheating the combustion air passed into the cupola, and a suitable conveyor means is provided for continuously discharging the mixture of carbonaceous material and mineral matter into an upper portion of the cupola.

By this invention a continuous method has been provided for the preparation of a melt of mineral matter from a mixture of finely divided mineral matter and carbonaceous material, such as slack coal. This melt may be blown by a high pressure steam jet into a mineral wool product. However, if desired, other products may be prepared from the melt, such as defluorinated phosphate rock which is suitable for use as a fertilizer. Defluorination may be effected by passing a quantity of steam over the mixture of a fluorine-containing phosphate and a carbonaceous material undergoing combustion before introduction into the cupola. Alternative or supplementary defluorination may also be effected by treating the phosphate melt discharged from the cupola, with steam at low pressure to form pellets of a defluorinated phosphate which latter may be used as a fertilizer.

For a more complete understanding of this invention, reference will now be had to the drawings forming a part of this specification, in which

Fig. 1 is a longitudinal central sectional elevation through the apparatus:

Fig. 2 is a transverse sectional elevation through the apparatus taken along the line 2—2 of Fig. 1; and

Fig. 3 is an enlarged cross-section through the cupola taken along the line 3—3 of Fig. 2.

The improved cupola furnace of this invention comprises a suitable framework 10 for supporting the various elements of the structure. A pit 12 is provided to receive a mixture of slack coal and mineral matter, and a bucket conveyor 14 is provided for removing the mixture from the pit 12 and delivering the mixture to a hopper 16 positioned above a moving chain grate stoker 18 positioned adjacent the lower floor of a combustion chamber 20. Air ducts 22, controlled by dampers 24, are positioned below the upper reach of the chain grate stoker 18 and a manifold 26 connects a blower 28 to the ducts 22 for supplying air for combustion purposes to and through the mixture of slack coal and mineral matter on the chain grate stoker 18. The chain grate stoker 18 moves in the direction indicated by the arrow in Fig. 1 towards a chute 30 which is positioned above a cupola 32 and is so arranged that the material deposited on the stoker 18 from the bin 16 will be discharged into the top of the cupola 32.

The cupola 32 comprises an elongated upright chamber having an oval cross-section which is provided with side walls lined with a plurality of vertically extending steam generator tubes 34 connected to an upper manifold 36 and a lower manifold 38. As most clearly shown in Fig. 3, refractory cement 40 extends between the tubes 34, and a layer of mineral wool 42 extends between a metal shell 44 and the refractory cement 40.

As shown most clearly in Fig. 1, the upper end of the cupola 32 opens into the combustion chamber 20 so that gases from the cupola and air from the ducts 22 passing through the grate stoker 18 may be combined. In the upper portion of the combustion chamber 20 is positioned a boiler 46 mounted within a setting 48. A plurality of boiler tubes 50 extend longitudinally through the boiler 46 and provide passageways between the combustion chamber 20 and a stack 52, thereby providing means for discharging hot combustion gases from the combustion chamber. Surrounding the stack 52 are preheating jackets 54, 56, and 58 (see Fig. 2), having a blower 60 associated therewith for forcing intake air through a duct 62, which is connected to the jacket 54, and ducts 64 and 66 which are connected to jackets 54, 56 and 58 in series. A duct 68 extends from the jacket 58 to a bustle box 70 which surrounds a medial portion of the cupola 32. Tuyères 72 are provided for injecting preheated air from the bustle box 70 to the lower portion of the cupola 32 to accelerate the combustion of the coke therein, whereby the mineral matter associated therewith is fused. Adjacent a lower edge of the floor of the cupola 32 is located a spout or port 74 through which the melt is discharged to a point near a steam blowing nozzle 76 which disintegrates the mineral melt into mineral wool. The nozzle 76 is positioned to discharge the blown fibers to a blow chamber 78 through an opening 80 whereby the fibers are deposited on a conveyor 82 to form a mat 84 of mineral wool.

In order to provide cold make-up water for the steam generating system of the apparatus, an intake water pipe 86 connects with pipes 88 pass-

ing in series through a refractory arch 90 which extends obliquely into the combustion chamber 20 above the cupola 32. This arch serves not only to carry the pipes 88 for preheating the make-up water but also lengthens the path of travel of the gases of combustion from the cupola into the combustion chamber so as to make the combustion more complete. A pipe 92 is provided for removing the preheated water from the pipes 88 within the arch 90 and connects with a cylinder 94 of a water pump which is operated by a steam cylinder 96. A pipe 98 having a check valve 100 extends between the cylinder 94 and a circulating pipe 102 for discharging the preheated water into the lower manifold 38 surrounding the cupola 32. A blow-off valve 104 is provided in the manifold 38 to discharge sludge from the system when necessary. A steam pipe 106 connects the upper manifold 36 of the cupola 32 and the boiler 46. Water is withdrawn from the boiler 46 by a pump 108 through a line 110 and circulated through the line 102 to the lower manifold 38 of the cupola 32. As shown, a steam drum 112 is provided in the top of the boiler 46 and a steam pipe 114 leads therefrom for conducting high pressure steam to the wool blowing nozzle 76. A branch steam pipe 116 leads from the pipe 114 to the steam cylinder 96, the flow of steam through said pipe 116 being controlled by a valve 118. A branch pipe 120 controlled by valve 122 leads from the steam pipe 114 to the duct 68 so that steam, if desired, may be introduced into the cupola 32 through the tuyères 72 in order to assist in certain chemical reactions such as the defluorination of phosphate rock.

A charging door 124 is provided in the furnace setting 48 above the cupola 32 so that fuel may be manually added to said cupola if desired. A clean-out door 126 is also provided in the setting 48 above the arch 90.

In the operation of the above described apparatus, coal slack and mineral matter are dumped into the pit 12 and the mixture is carried by the bucket conveyor 14 to the hopper 16 and is discharged through a suitable gate onto the chain grate stoker 18. The mineral matter mixed with the coal slack may be granulated slag, small size rock, coarse sand or gravel, clay, phosphate rock, or similar material. Other forms of carbonaceous material may be substituted for the slack coal if desired. For example, under certain conditions it may be desirable to employ petroleum coke or a heavy petroleum pitch. The relative amounts of mineral matter and carbonaceous material may be adjusted so that the combination of the charged mineral matter combined with the ash of the carbonaceous material produces a melt having the desired composition. The mixture of carbonaceous material and mineral matter on the chain grate stoker 18 is continuously advanced toward the chute 30. The high temperature within the combustion chamber causes the volatile matter to be distilled from the slack coal or other carbonaceous material on the stoker surface and the volatile matter admixed with air passed through the stoker from the ducts 22 burns within the combustion chamber 20. These hot products of combustion pass through the tubes 50 of the tube boiler 46 to generate steam therein and they thereafter pass out through the stack 52. The heating and partial distillation of the material on the chain grate stoker 18 causes the slack coal or other carbonaceous material to carbonize to form a coke which coalesces with the mineral matter to form relatively large pieces

or chunks of a mixture of coke and mineral matter. These pieces are discharged from the stoker 18 over the chute 30 into the cupola 32. Within the cupola the carbonaceous mixture is caused to burn at temperatures sufficient to form a melt of the mineral matter by reason of the preheated air passing into the cupola through the tuyères 72 from the bustle box 70, this air having been preheated in the stack jackets 54, 56 and 58 that are connected thereto as hereinbefore described. The fused mineral matter flows in a stream through the port 74 and is blown into mineral wool by the steam nozzle 76. The mineral wool deposits on the conveyor 82 in the blow chamber 78 in the form of a mat 84.

Hot water under pressure circulates in the system from the boiler 46 through the pipe 110, the circulating pump 108, the pipe 102, the manifold 38, the steam generating tubes 34, the manifold 36 and the pipe 106. Cold make-up water is supplied as needed through the pipe 86, the preheating pipes 88 in the arch 90, the pipe 92, the water pump 94, and the pipe 98, into the pipe 102. Steam passes from the steam drum 112 associated with the boiler 46 through the pipe 114 to the nozzle 76 and through the pipe 116 to the steam cylinder 96. The steam generated in the steam generating tubes 34 of the cupola 32 passes through the pipe 106 to the boiler 46 along with the circulating water.

The carbonaceous mixture that is deposited on the stoker 18 from the bin 16 should be spread in a relatively thin layer over the upper surface of the stoker to permit the free passage of air therethrough from the ducts 22, and to permit the layer to be heated throughout its entire thickness. This will permit of the formation on the stoker of a sintered mass which is porous in nature and which may be readily and easily fired within the cupola 32 because it does not have a tendency to pack, thereby preventing the passage of combustion gases therethrough. It will be clear, of course, that the carbonaceous material and mineral matter may be deposited upon the surface of the chain grate stoker 18 in separate layers if so desired. In such case two bucket conveying systems may be employed to effect this result.

As most clearly indicated in Fig. 3, the melting chamber within the cupola 32 has an oval cross-section and the cupola is disposed with respect to the stoker so that the maximum diameter of the cupola extends transversely to the direction of movement of the stoker. The sintered mass of carbonaceous material and mineral matter is thus more readily deposited within the cupola and a more even temperature within the cupola is obtainable than would be the case if the cross section thereof were circular.

From the above description it will appear that a process and apparatus have been described for producing a stream of mineral melt the flow of which from the cupola remains substantially constant or may be regulated as desired. The rate of flow of the melt may be controlled by regulating the speed of the belt conveyor 14 and the chain grate stoker 18, the mineral matter in the mixture being supplied to the top of the cupola at substantially the same rate as it is desired to withdraw the melt from the bottom thereof through the spout 74.

It is apparent that the cupola furnace of this invention carries out a two stage process, viz: an initial stage in which the volatile matter is distilled from the coal to produce large pieces of a

sintered mixture of coke and mineral matter, and a second stage in which the pieces of this mixture are completely burned at a high temperature to produce molten mineral matter which is blown into mineral wool. The coking step is carried out with the coal lying on the stoker in a shallow layer so that it can be readily heated and coalesced and so that air for combustion can readily pass through the sintering mixture. The second or melting step is carried out while the large pieces are maintained in a comparatively deep column. In the second step, the fuel is in the form of pieces of coke which readily permit the passage of the preheated air and combustion gases therethrough and the carbonaceous material has passed the plastic stage where it will tend to coalesce within the cupola. Thus fusion of the mineral matter is more readily effected in the cupola. The process is especially advantageous because of the low cost of the materials which may be used including coal fines, or even slack coal having a high ash content, and fine mineral matter which is ordinarily discarded as waste. The cupola furnace also produces its own steam for blowing purposes, and utilizes most of the waste heat so that stack gases are discharged at the lowest possible temperature. The mixture of coal and mineral matter is automatically fed to the furnace thus greatly reducing the labor of operation incident to hand firing heretofore used.

The apparatus is suited for a variety of uses other than the production of mineral wool. For instance, it may be used for the smelting of ores, such as iron ore. As another example, gypsum might be included in the mineral mixture so that sulfur dioxide and sulfuric acid becomes one of the by-products. The apparatus might also be used for the defluorination of phosphate rock in the production of phosphate fertilizer or even elemental phosphorus. In this type of reaction, the steam introduced into the cupola enters into the reaction to accomplish the defluorination of the rock. Low temperature steam may be used at the nozzle 76 in defluorination so that pellets of fused phosphate rock are produced instead of wool. Defluorination may also be effected by mixing steam with the air which is passed through the mixture of mineral matter and carbonaceous material on the stoker 18.

It will be recognized that the fuel and mineral matter may be thoroughly mixed before it is initially charged into the receiving pit. This mixing may be effected in any type of mixing machine (not shown) such as one which is useful for mixing concrete. In such case, the fuel and mineral matter may be stored in separate storage bins (not shown) and withdrawn in desired quantities and supplied to the mixer. The resulting mixture having a predetermined composition may then be charged to the receiving pit 12 and thereafter passed through the cupola furnace as hereinbefore described.

While a particular embodiment of this invention is shown above, it will be understood, of course, that the invention is not to be limited thereto, since many modifications may be made, and it is contemplated, therefore, by the appended claims, to cover any such modifications as fall within the true spirit and scope of this invention.

I claim:

1. The process of producing fused mineral matter by a continuous process which comprises admixing mineral matter with a carbonaceous fuel containing volatile matter in substantial quan-

tities, passing the resulting mixture on a conveyor through an enclosed combustion zone wherein said volatile matter is burned from the fuel and a sintered mass of mineral matter and coke-like material is formed, discharging the resulting sintered mass in lump form into a separate high temperature melting and oxidizing zone wherein said coke-like material is burned thereby fusing said mineral matter, and substantially continuously removing said fused mineral matter from said oxidizing zone.

2. The method of producing a stream of molten mineral matter, which comprises moving a mixture of solid carbonaceous fuel initially containing volatile matter in substantial quantities and solid mineral matter in a shallow layer through an enclosed combustion zone, heating said layer therein under oxidizing conditions so as to distill and burn the volatile matter from said fuel and to produce substantially large pieces of a sintered mixture of coke-like material and mineral matter, introducing said pieces into a vertical combustion chamber provided with means for forcing combustion-supporting gases therethrough, completing the combustion of the carbonaceous fuel in said chamber whereby to produce gaseous products of combustion and fused mineral matter, and withdrawing said fused mineral matter in a stream from the bottom of said chamber.

3. The method of continuously producing a melt suitable for blowing into mineral wool which comprises continuously moving a mixture of coal and potentially fusible mineral matter in a shallow layer in an enclosed combustion zone, heating said layer under oxidizing conditions therein so as to distill and burn volatile matter from said coal and to produce substantially large pieces of a sintered mixture of coke and mineral matter, continuously introducing said pieces into a combustion chamber provided with positive means for forcing combustion-supporting gases therethrough, and completing the combustion of the coke in said chamber to produce gaseous products of combustion and fused mineral matter.

4. The process of producing fused mineral matter by a continuous process which comprises admixing a finely divided carbonaceous fuel containing volatile matter in substantial quantities with finely divided mineral matter, continuously advancing the resulting mixture on a conveyor through a primary combustion and heating chamber whereby the fuel is incompletely burned to distill off the volatile matter and a sintered mass of mineral matter and coke-like material is formed, continuously discharging said sintered mass in lump form into a separate high temperature melting cupola wherein said coke-like material is burned thereby fusing said mineral matter, and continuously removing said fused mineral matter from said cupola.

5. The method of heat treating a substance, which comprises continuously moving a mixture of carbonaceous fuel and mineral matter in a shallow layer, subjecting said layer to oxidizing conditions so as to distill and burn volatile matter from said mixture and to produce a sintered mixture of coke and mineral matter, assembling said sintered mixture in a combustion chamber, passing preheated air through said assembled mixture whereby to burn said coke and continuously to produce a mass of fused mineral matter, and continuously withdrawing said fused mineral matter from said combustion chamber.

6. In an apparatus of the class described, a furnace setting, a boiler within said setting, a

stoker within said setting and spaced from said boiler, a cupola associated with said stoker, means for supplying a mixture of solid fuel and mineral matter to said stoker to be sintered and incompletely burned, means for supplying a combustion-supporting gas to the mixture on said stoker, means for removing said sintered mixture from said stoker into said cupola, said cupola having walls comprising a series of vertically arranged water tubes, means for completing the combustion of carbon in said mixture within said cupola to form fused mineral matter, and means for circulating water between said boiler and the water tubes of said cupola whereby to generate steam.

7. In an apparatus of the class described, a housing, a chain grate stoker in said housing, a receiving pit, a feed hopper associated with said stoker, conveyor means for delivering a mixture of solid fuel and mineral matter from said pit to said hopper, said hopper being arranged to deliver a shallow layer of said mixture on said stoker, means for sintering and partially burning the mixture on said stoker, a cupola, means for delivering said mixture to said cupola to be completely burned to form molten mineral matter, and means for withdrawing said fused mineral matter from said cupola.

8. An apparatus of the character described which comprises a first combustion chamber, a conveyor within said chamber, means for supplying a mixture of solid fuel and mineral matter to said conveyor, means for supplying combustion-supporting gases to the mixture on said conveyor whereby said mixture is sintered and the fuel therein is incompletely burned, a second combustion chamber opening into said first combustion chamber for receiving the sintered mixture from said conveyor, means for supplying additional combustion-supporting gases to said second combustion chamber completely to burn the fuel in the sintered mixture therein whereby to melt said mineral matter, and means for discharging the molten mineral matter from said second combustion chamber.

9. An apparatus of the character described which comprises a first combustion chamber, a stoker within said chamber, means for supplying a mixture of solid fuel and mineral matter to said stoker whereby said mixture is advanced within said chamber, means for supplying combustion-supporting gases to the mixture on said stoker whereby to sinter the mixture and incompletely to burn the fuel in said mixture thereby liberating hot combustion gases, a second combustion chamber positioned adjacent the discharge end of said stoker communicating with said first combustion chamber, means for supplying additional combustion-supporting gases to said second combustion chamber completely to burn the fuel in said mixture therein whereby to melt said mineral matter, means for withdrawing combustion gases from said apparatus, and means for discharging the molten mineral matter from said second combustion chamber.

10. An apparatus of the character described which comprises a first combustion chamber, a boiler positioned in the upper reaches of said chamber, a stoker within said chamber spaced from said boiler, means for supplying a mixture of solid fuel and mineral matter to said stoker whereby said mixture is advanced within said chamber, means for supplying combustion-supporting gases to the mixture on said stoker whereby to sinter the mixture and incompletely to burn the fuel in said mixture thereby liberat-

ing hot combustion gases, a second combustion chamber positioned adjacent the discharge end of said stoker communicating with said first combustion chamber, means for supplying additional combustion-supporting gases to said second combustion chamber completely to burn the fuel in the sintered mixture whereby to melt said mineral matter and to form additional hot combustion gases, means for passing the combined hot combustion gases from the combustion chambers into heat exchange relationship with said boiler prior to discharge from the apparatus, and means for discharging the molten mineral matter from said second combustion chamber.

11. An apparatus of the character described which comprises a first combustion chamber, a boiler positioned in the upper reaches of said chamber, a stoker within said chamber spaced from said boiler, means for supplying a mixture of solid fuel and mineral matter to said stoker whereby said mixture is advanced within said chamber, means for supplying combustion-supporting gases to the mixture on said stoker whereby to sinter the mixture and incompletely to burn the fuel in said mixture thereby liberating hot combustion gases, a second combustion chamber positioned adjacent the discharge end of said stoker communicating with said first combustion chamber, means for supplying additional combustion-supporting gases to said second combustion chamber completely to burn the fuel in the sintered mixture whereby to melt said mineral matter and to form additional hot combustion gases, means for admixing the hot combustion gases from each combustion chamber, means for passing the combined hot combustion gases into heat exchange relationship with said boiler prior to discharge from the apparatus, means for discharging the molten mineral matter from said second combustion chamber, steam-generating tubes associated with said second combustion chamber, means for circulating water and steam from said boiler to said steam-generating tubes, and means for discharging generated steam from said boiler.

12. An apparatus for the continuous production of a melt suitable for blowing into mineral wool, from mineral matter and a finely divided carbonaceous fuel containing volatile matter in substantial quantities, which comprises, a primary sintering and combustion chamber, a stoker for continuously passing a mixture of said mineral matter and said fuel in a shallow layer through said sintering and combustion chamber whereby the mixture is sintered to form large lumps, a vertical melting chamber positioned ad-

jacent the discharge end of said stoker adapted to receive said lumps, means for supplying a combustion-supporting gas to said melting chamber whereby said fuel in the mixture is burned to melt said mineral matter and to produce hot combustion gases, said melting chamber being open to said primary chamber whereby the hot combustion gases pass to the latter to assist in the sintering operation, and means for continuously discharging molten mineral matter in a stream from the melting chamber as rapidly as it is formed.

13. An apparatus for the continuous production of a melt suitable for blowing into mineral wool, from mineral matter and finely divided coal which comprises, a primary sintering and combustion chamber, a steam boiler within said chamber, a stoker for continuously advancing a mixture of said mineral matter and said coal in a shallow layer through said chamber whereby said mixture is sintered to form large lumps of a mixture of coke-like material and mineral matter, a vertical melting chamber having steam-generating tubes embedded in the side walls thereof, said melting chamber being positioned adjacent the discharge end of said stoker whereby to receive said lumps, means for supplying a combustion-supporting gas to said melting chamber whereby said coke-like material in the mixture is burned to melt said mineral matter and to produce hot combustion gases, said melting chamber being open to said primary chamber whereby the hot combustion gases pass to the latter to assist in the sintering operation, means for circulating water and steam from the steam-generating tubes to the boiler, means for supplying make-up water to the boiler, and means for continuously discharging molten mineral matter in a stream from the melting chamber as rapidly as it is formed.

14. The method of heat-treating a mixture containing a finely divided fuel and a fusible material by a continuous method which comprises advancing the mixture in a shallow layer on a conveyor through a first combustion zone under conditions controlled to permit said fuel to be incompletely burned to produce sintered lumps of a mixture of coke-like matter and fusible material, discharging said lumps as rapidly as they are formed from the conveyor into a second combustion zone, passing a combustion-supporting gas into said second zone to burn the coke-like matter in the mixture whereby to melt the fusible material, and continuously withdrawing the melted material from said second combustion zone.

WILLIAM M. MCNEIL.

Certificate of Correction

Patent No. 2,395,231.

February 19, 1946.

WILLIAM M. McNEIL

It is hereby certified that errors appear in the printed specification of the above numbered patent requiring correction as follows: Page 1, second column, line 41, for "th melt" read *the melt*; page 5, second column, line 19, claim 13, for "coil" read *coal*; and that the said Letters Patent should be read with these corrections therein that the same may conform to the record of the case in the Patent Office.

Signed and sealed this 14th day of May, A. D. 1946.
